US00D653953S

(12) **United States Design Patent**
Wakeman et al.

(10) **Patent No.:** US D653,953 S
(45) **Date of Patent:** ** Feb. 14, 2012

(54) **SQUEEZE BOTTLE**

(75) Inventors: **Michael Wakeman**, Boulder, CO (US);
William Stephens, Boulder, CO (US)

(73) Assignee: **Water Pik, Inc.**, Fort Collins, CO (US)

(**) Term: **14 Years**

(21) Appl. No.: **29/352,093**

(22) Filed: **Dec. 16, 2009**

(51) **LOC (9) Cl.** 09-01

(52) **U.S. Cl.** D9/526; D9/575

(58) **Field of Classification Search** D9/434,
D9/435, 516, 523, 526, 530, 537, 540, 545,
D9/549, 682, 686, 688-690, 723, 724; 215/381-385,

(57) **CLAIM**

The ornamental design for a squeeze bottle, as shown and described.

DESCRIPTION

FIG. 1 is a front isometric view of a squeeze bottle;
FIG. 2 is a right elevation view of the squeeze bottle of FIG. 1;

FIG. 3 is a left elevation view of the squeeze bottle of FIG. 1;
FIG. 4 is a front elevation view of the squeeze bottle of FIG. 1;

FIG. 5 is a rear elevation view of the squeeze bottle of FIG. 1;
FIG. 6 is a top plan view of the squeeze bottle of FIG. 1; and,
FIG. 7 is a bottom plan view of the squeeze bottle of FIG. 1.
The broken lines seen on the FIG. 7 bottom view represent the
bounds of the claimed design while all other broken lines are
included for the purpose of illustrating the unclaimed portions
of the article; the broken lines form no part of the
claimed design.

1 Claim, 6 Drawing Sheets
